Thurston & Bates.

UNITED STATES PATENT OFFICE.

SAMUEL E. STRONG, OF CLEVELAND, OHIO.

DESIGN FOR AN ATOMIZER.

SPECIFICATION forming part of Design No. 27,257, dated June 29, 1897.

Application filed February 9, 1897. Serial No. 622,668. Term of patent 14 years.

To all whom it may concern:

Be it known that I, SAMUEL E. STRONG, a citizen of the United States, residing at Cleveland, in the county of Cuyahoga and State of Ohio, have invented and produced a new, useful, and original Design for Atomizers, of which the following is a full, clear, and exact description, reference being had to the accompanying drawings, forming a part thereof.

In the drawings, Figure 1 is an elevation of a tube formed in accordance with my design, the size there shown being a convenient one for actual use; and Fig. 2 is a longitudinal central section through both necks.

The leading features of my invention consist of a round glass tube having one end closed and having at the other end two necks, each of which has a longitudinal capillary orifice and is embraced by a metal ferrule with a removable cap on its end. By the expression "round" tube I mean to include not only tubes which are cylindrical, but tubes

which are more or less perfect ellipses in transverse section, because obviously the appearance of the different forms suggested will 25 be substantially the same.

Referring to the parts by letter, A represents an approximately cylindrical glass tube having an approximately hemispherical closed end a. At the other end are two necks 30 a' a², each of which has a longitudinal capillary orifice a³ a⁴.

B' B represent ferrules embracing the necks, and C' C² removable caps.

What I claim is—

The design for an atomizer, substantially as shown and described.

In testimony whereof I affix my signature in presence of two witnesses.

SAMUEL E. STRONG.

Witnesses:

A. A. BURGESS,
E. L. THURSTON.
